UNITED STATES PATENT OFFICE.

WILLIAM B. POTTER, OF SCHENECTADY, NEW YORK, ASSIGNOR TO GENERAL ELECTRIC COMPANY, A CORPORATION OF NEW YORK.

THIRD-RAIL ANCHORAGE.

No. 909,335.

Specification of Letters Patent. Patented Jan. 12, 1909.

Application filed September 7, 1907. Serial No. 391,769.

To all whom it may concern:

Be it known that I, WILLIAM B. POTTER, a citizen of the United States, residing at Schenectady, in the county of Schenectady and State of New York, have invented certain new and useful Improvements in Third-Rail Anchorages, of which the following is a specification.

My invention relates to anchorages for rails, and is particularly designed for use in connection with the third-rails of electric railways.

Experience has shown that, owing to expansion and contraction due to changes in temperature, rails often gradually move in a lengthwise direction. This is especially true of third-rails which are not, of course, as rigidly supported as are traction rails. While there are many ways of supporting third-rails one, which has been found to be especially successful, consists simply in mounting the rail on blocks of insulation resting on the ends of certain of the rail ties, which are made especially long for this purpose. With this method of support the rail is not secured to the insulating block but simply rests thereon by its own weight, a manner of support which is satisfactory since the third-rail shoe bears on the top of the rail and exerts no force which might tend to displace it. With third-rails supported in this manner "creeping" becomes particularly excessive and objectionable, since the only thing that tends to restrain longitudinal movement of the relay is the friction between it and the supporting blocks of insulation.

It is an object of my invention to provide an anchorage which, while it is not limited in its application to third-rails supported in any particular way, will serve particularly well to hold rails supported as above described and prevent creeping thereof.

My invention also has for its object the provision of means whereby short stretches of third-rail may be held down and all chance of their being displaced by a defective third-rail shoe removed.

My invention will be understood by reference to the accompanying drawing, in which—

Figure 1 is a plan view of a portion of a railroad track with an adjacent third-rail having my improved anchorage applied thereto; Fig. 2 is an elevation of said third-

rail and anchorage; and Fig. 3 is a cross-section through the third-rail showing one of the clamps which grip it.

Referring to Fig. 1, 5 represents one of the traction rails which is secured to the ties 6 in any suitable manner. The third-rail is indicated at 7, is mounted in a well known manner on insulating blocks 8 from the top of which extend lugs 9 which serve to hold the rail from lateral displacement. The insulating blocks 8 may have a square hole in their bottom which fits the head of a bolt 10 secured to the tie.

While my anchorage might be applied to any point on the rail, it is preferably used at one of the supporting points and I have so shown it applied. In the form of anchorage shown, which I have found satisfactory, two clamps 12 and 13 each consisting of two parts, the form of which is well shown in Figs. 2 and 3, are secured to the bottom of the third-rail by bolts 14. These bolts draw the two parts of the clamps together and cause them to firmly grip the rail. Another bolt 15 is passed through holes in the bottom of each clamp, and to this is secured a bolt connection extending to some fixed point on the road-bed, as, for example, the tie 6, upon which the supporting block 8 rests. This bolt connection may comprise a strain insulator 16, of any suitable form, having secured to one side a lug 17 having an eye through which the bolt 15 is passed, and on its other end a rod 18 which may be screwed into it or otherwise attached. The rod 18 may be passed through a hole in the tie 6, and nuts 19 may secure it against withdrawal. In order to increase the rigidity of the tie, to which the anchorage is applied, a brace 20 may be bolted to this tie and to one or more ties one each side of it, as clearly shown in Fig. 1.

The operation of my improved anchorage is obvious. The clamp and bolt connection between the third-rail and the tie on each side thereof effectively secures the rail against longitudinal movement in either direction. Owing to the fact that the bolt 15 is some distance from the bottom of the rail any pull exerted on this bolt will tend to jam the clamp more tightly against the rail, thereby preventing any possibility of the clamps slipping. It is apparent that the arrangement shown, if applied at intervals along the line, not only prevents longitudinal movement of the rail, but also secures the rail against lateral displacement.

nal movement of the rail, but also may be used to hold it down in contact with the supporting blocks and thus prevent possible displacement where short stretches of third-rail exist. The strain insulators interposed in the bolt connections between the clamps and the tie prevent grounding of the third-rail. While I have shown but one form in which my invention may be embodied, I wish it understood that I realize that it may be modified in many respects without departing from the spirit thereof. It is my intention to cover all such modifications in the following claims.

15. What I claim as new and desire to secure by Letters Patent of the United States, is,
1. In combination, a third rail, supports therefor, and an anchorage for said rail comprising clamps secured to said rail, bolt connections located beneath said rail and extending in opposite directions from said clamps to the road-bed, and an insulator interposed in each bolt connection.
  2. In an electric railway, traction rails, ties upon which said rails are mounted, a third rail also supported on said ties, an anchorage for said rail comprising clamps secured to said rail, bolt connections located beneath said rail and extending in opposite directions from said clamps to a tie, and an insulator interposed in each bolt connection.

3. In an electric railway, traction rails, ties upon which said rails are mounted, a third-rail also supported on said ties, and an anchorage for said third-rail comprising clamps bolted to said third-rail, and insulated bolt connections extending in opposite directions from said clamps to a tie.

4. In an electric railway, traction rails, ties upon which said rails are mounted, certain of the ties being longer than others, a third rail and insulated supports therefor mounted on the longer ties, and an anchorage for said third-rail comprising an insulated connection between said third-rail and one of the ties upon which it is supported.

5. In an electric railway, traction rails, ties upon which said rails are mounted, certain of said ties being longer than others, a third rail and insulated supports therefor mounted upon the longer ties, and an anchorage for said third-rail comprising clamps secured to said rail on opposite sides of a supporting tie, and bolts and strain insulators for connecting said clamps and the tie.

In witness whereof, I have hereunto set my hand this 5th day of September, 1907

WILLIAM B. POTTER.
